T. C. VAN EPPS

TIDE OPERATED AIR COMPRESSOR

Filed May 25, 1927

Inventor
Theodore C. Van Fossen
by Hazard and Miller
Attorneys.

UNITED STATES PATENT OFFICE.

THEODORE C. VAN EPPS, OF LOS ANGELES, CALIFORNIA.

TIDE-OPERATED AIR COMPRESSOR.

Application filed May 25, 1927. Serial No. 194,067.

This invention relates to power machines, and more particularly to a tide operated pressure generator adapted to convert the power possessed by rising water into mechanical energy, and to convert the potential energy possessed by a float which forms an element of my device, into energy.

A further object of this invention is to devise a means whereby the power of rising and falling ocean tides may be converted into energy to be applied to various kinds of machinery for driving the same.

A still further object of the invention is to provide a device which is strong and durable, possesses a minimum number of movable parts, is unlikely to get out of order, will last indefinitely in service, is inexpensive to manufacture, and performs the function required of it in an efficient and simple manner.

With these and many other objects in view which will more readily appear as the nature of the invention is better understood, the same consists in the novel construction, combination and arrangement of parts, which will hereinafter be more fully described, illustrated, and claimed.

The essential features of the invention involved in the carrying out of the objects indicated are susceptible to modification; but a preferred embodiment of the invention is shown in the accompanying drawings, in which:

Figure 1 is a sectional view taken through my device showing the same in assembled relationship in the position it assumes at low tide.

Fig. 2 is a top plan view of the device.

Fig. 3 is a view of the preferred form of motor generator used in connection with my device.

Fig. 4 is a side view of the motor generator.

Fig. 5 is a diagrammatic view showing the operative connections whereby power is led from a series of the pressure generators to a storage tank.

The various figures described above adequately illustrate my invention, and the following detailed description is commensurate with the above mentioned drawings in enabling an artisan to construct and assemble the constituent parts of the same.

The device involves in its general organization, a plurality of piles 10 and 11, which piles are driven into the ocean bed as at 12, and extend upwardly above the surface of the water. A substantially rectangular frame work hav-

ing side bars 13 and end bars 14 are attached to these piles 10 and 11 in such a manner as to overlie the surface of the water. Guides 15 are secured to this frame work and extend vertically for a purpose to be described hereinafter. A plurality of cross bars 16 extend across the side bars 13 and guide bearings 17 are formed in these cross bars. A pontoon 20 is mounted centrally of the frame work and rests upon the surface of the water. This pontoon has a superstructure 21 composed of pilasters 22, and a top frame work formed of cross bars 23 extending across the pilasters 22. The pilasters 22 are slidably received in the guide bearings 17, and suitable rollers 24 serve to guide the pontoon vertically so that the same may rise or fall as the surface of the ocean rises or falls. Secured to the underfaces of the super-structure and to the cross bars 16 respectively, are a pair of inverted annular shells A and B, and secured to the upper surface of the pontoon 20 and to the upper side of the cross bars 16 are a pair of upright shells C and D respectively. These two last mentioned shells surround and are concentric with inner shells E and F. The diameters of the shells A and B are such as to enable the same to be telescoped into the shells D and C respectively, and the diameters of the shells E and F are such as to enable them to be telescoped into the shells A and B respectively. A suitable liquid such as water is disposed between the shells D and E and between the shells C and F, and annular packing glands 30 and 31 are formed on the inner surface of the shells C and D respectively, and thus above and below the cross bars 16 are formed a pair of collapsible tanks. These tanks as an entirety are designated at M and N. The tank M is provided with an outlet 33, which outlet leads through a pipe 34. The tank N is provided with an outlet 35 leading through a pipe 36, and the pipes 34 and 36 lead to a common outlet 37 which leads to a collapsible storage tank having sections 38 and 39 as shown in Figure 5. Check valves are designated at 47 and 48, the check valve 47 providing an air inlet for the tank M, and the check valve 48 providing an air inlet for the tank N.

From the foregoing it is thought that the construction of my device will be apparent, and I will now proceed with the description of the operation of the same.

In actual operation the device is preferably installed within a break-water 50, and at low tide the device will assume the position

shown in Figure 1. In various localities of the country, particularly around the north-eastern part of the United States and around the Bay of Fundy, the tide rises to a considerable height, in some cases as high as seventy-two feet, and the device may be modified in accordance with the spirit of the invention to accommodate various heights of tide. At low tide the tank N is completely expanded and the tank M is collapsed. As the tide rises, the pontoon 20 which rests upon the surface of the water will be elevated, and a pressure will be created in the tank N. The check valve 48 will not permit air to escape from this tank, and the air will be forced through the pipes 36 and 37 to the storage tank 38. During this operation the tank M is expanding and air enters through the check valve 47. The check valves 60 permit no air to return to the tanks M and N from the storage tank. At high tide the tank M will be completely expanded and air will have been forced from the tank N under pressure. As the tide falls, the potential energy possessed by the pontoon, together with its superstructure, will cause the air to be expelled from the tank M as the same collapses, and during this operation air enters through the check valve 48. This operation is continuous.

In practicing my invention I contemplate using a plurality of these tanks as shown in Figure 5. These tanks may be connected to a common pipe line leading to the storage tank. From the storage tank compressed air may be led to a motor generator turbine or the like 70 of any conventional type, and thus electrical energy is developed, which energy may be used for any suitable purpose.

From the foregoing, it is thought that the construction, use and many advantages of the herein-described tide operated pressure generator will be readily apparent without further description, and it will also be understood that changes in the form, proportion and minor details of construction may be resorted to without departing from the spirit of the invention or sacrificing any of the advantages thereof. For example, I contemplate employing a concrete foundation in lieu of the piles 10, such change being resorted to within the spirit of the invention and scope of the claims.

What I claim by this invention and desire to secure by Letters Patent, is:

1. A tide operated compressor comprising in combination a pontoon, a super-structure above said pontoon, a stationary structure between said pontoon and superstructure, a collapsible tank attached to said pontoon and stationary structure, a second collapsible tank attached to said super-structure and stationary structure, and inlets and outlets for said tanks.

2. A tide operated compressor comprising in combination a pontoon, pilasters on said pontoon, a plurality of piles adapted to be driven into the ocean bed, a frame work attached to said piles, cross bars extending across said frame work and overlying said pontoon, guides in said cross bars adapted to receive said pilasters, a super-structure mounted on said pilasters, an inverted shell on said super-structure, an upright shell on said cross bars, a second inverted shell on said cross bars, an upright shell on said pontoon, said first and second mentioned shells being mounted concentrically and forming a tank, and said second and third mentioned shells being mounted concentrically and forming a tank, there being inlets and outlets from said tanks.

3. A device as claimed in claim 2, there being an inner shell in said last mentioned shell, and an inner shell in said second mentioned shell, and a fluid disposed between said inner shells and said second and fourth mentioned shells.

4. A device as claimed in claim 2, and in addition, there being check valves in said inlets and outlets for the purpose specified.

5. A device as claimed in claim 2, and in addition, guides on said frame work and rollers mounted on said pontoon for the purpose specified.

6. A tide operated compressor comprising in combination a pontoon, a superstructure above said pontoon, a stationary structure between said pontoon and superstructure, a collapsible tank attached to said pontoon and stationary structure and adapted to be collapsed when the pontoon is raised, a second collapsible tank attached to said superstructure and said stationary structure, and adapted to be collapsed when the pontoon is lowered, and inlets and outlets for said tanks.

7. A tide operated compressor comprising a plurality of piles adapted to be driven into the ocean bed, a pontoon adapted to be raised and lowered by the tides, the movement of said pontoon being limited to vertical movement by said piles, a framework rigid with said piles, an inverted shell supported by said piles, an upright shell on said pontoon in telescopic engagement with said inverted shell to provide a collapsible tank, a super-structure mounted on said pontoon, an inverted shell supported by said superstructure, an upright shell on said superstructure in telescopic engagement with said second mentioned inverted shell, to provide a second collapsible tank, check valved inlets on said tanks permitting air to flow therein, and outlet pipes connected to said tanks.

In testimony whereof I have signed my name to this specification.

THEODORE C. VAN EPPS.
